(57) **CLAIM**

The ornamental design for a dosing apparatus, as shown and described.

DESCRIPTION

FIG. 1 is a perspective view of one embodiment of a dosing apparatus showing our design;

FIG. 2 is a front elevational view thereof;

FIG. 3 right side elevational view thereof, the left side elevational view being a mirror image thereof;

FIG. 4 is a rear elevational view thereof;

FIG. 5 is a top plan view thereof;

FIG. 6 is a bottom plan view thereof;

FIG. 7 is a perspective view of another embodiment of the dosing apparatus showing our design;

FIG. 8 is a front elevational view thereof;

FIG. 9 is a right side elevational view thereof, the left side elevation view being a mirror image thereof;

FIG. 10 is a rear elevational view thereof;

FIG. 11 is a top plan view thereof; and,

FIG. 12 is a bottom plan view thereof.

The broken lines shown in the figures are for the purpose of illustrating portions of the dosing apparatus and form no part of the claimed design.

1 Claim, 10 Drawing Sheets(56)
